UNITED STATES PATENT OFFICE

95,729

DESIGN FOR A FACIAL SUPPORT

Florence Lund Brown, Chicago, Ill.

Application February 5, 1934, Serial No. 50,608

Term of patent 7 years

To all whom it may concern:

Be it known that I, Florence Lund Brown, a citizen of the United States, residing at Chicago, in the county of Cook and State of Illinois, have invented a new, original, and ornamental Design for a Facial Support, of which the following is a specification, reference being had to the accompanying drawing, forming part thereof.

In the drawing:

Fig. 1 is a side view slightly in perspective of the facial support embodying my design as it appears in use;

Fig. 2 is a side view of the facial support disclosed in Fig. 1; and

Fig. 3 is a front perspective view thereof.

I claim:

The ornamental design for a facial support, as shown.

FLORENCE LUND BROWN.
